ANIMAL FEED CONTROL RESERVOIR

Gerald L. Kitson, 9709 Belding Road,
Rockford, Mich. 49341

Filed Aug. 15, 1972, Ser. No. 280,820

Term of patent 14 years

Int. Cl. D30—03

U.S. Cl. D30—13

FIG. 1 is a side elevation of an animal feed control reservoir embodying my new design, the hidden side being a mirror image of that shown.

FIG. 2 is a front elevation for an animal feed control reservoir shown in FIG. 1.

FIG. 3 is a rear elevation for an animal feed control reservoir shown in FIGS. 1 and 2.

FIG. 4 is a top plan view for an animal feed control reservoir shown in FIGS. 1, 2 and 3.

FIG. 5 is a bottom view for an animal feed control reservoir shown in FIG. 1.

I claim:

The ornamental design for an animal feed control reservoir, as shown and described.
